UNITED STATES PATENT OFFICE.

ARNOLD REDLER, OF SHARPNESS, ENGLAND.

CONVEYER FOR SUBSTANCES IN A FINE OR LOOSE STATE OF DIVISION.

Application filed May 24, 1921. Serial No. 472,178.

To all whom it may concern:

Be it known that I, ARNOLD REDLER, of Flour Mills, Sharpness, in the county of Gloucester, England, a subject of the King of Great Britain and Ireland, have invented certain new and useful Improvements in or Relating to Conveyers for Substances in a Fine or Loose State of Division, of which the following is a specification.

10 This invention relates to conveyers for substances in a granular flocculent fine or loose state of division.

In conveyers as hitherto made formed of belts of rubber, cotton or similar material 15 working in a trough, the belt, with or without slats attached, supports and carries the material on the upper run, the belt is distinguished from an open structure in not permitting the material to fall through any 20 opening in the bottom of the trough over which bottom the conveyer travels. In a coal conveyer where an open link arrangement has been employed the coal is conveyed by the chain which is designed with 25 deep links to form chambers in which the coal lies to the depth of such chambers the links being so deep that the chain could not be pulled through the material in case of the outlet being choked without materially increasing the power or breaking the chain. 30 In conveyers of the creeper type in which the material is drawn along the trough by the bottom of the band to which slats or battens are attached at intervals, the creeper 35 relies on the direct action of the slats to push the material along. In such a conveyer the material cannot fall through the belt itself, but permits any material below it to fall through any aperture in the base 40 of the trough.

In a creeper formed of chain like structure in which both upper and lower runs are in a casing or trough, the slats are generally of large dimensions and far apart, the material being only just in front of each slat, and not filling the gap between the links, and does not form an improvised support for conveying the load, moreover should a block occur the slats cannot be drawn through the 45 material without increasing the power, or risk of breaking the conveyer.

A conveyer made in accordance with this invention comprises a series of links forming a continuous chain-like structure, or a

series of battens, bars, slats or the like 55 mounted on or between chains, ropes, links or the like forming a continuous open structure adapted to travel with both upper and lower runs in a closed casing or similar structure of metal, wood, concrete or other 60 suitable material, with or without a division between the upper and lower runs, the link work being of such dimensions and so constructed that it will with the bottom stratum of the substance to be transported when 65 travelling on the surface without apertures, form an improvised solid band on which to carry the remainder of its load. Said link work being of such pitch and width as to allow the substance to drop through when 70 passing over a suitable discharge orifice in the surface over which it is travelling, and is further characterized in that the depth of the transverse bars or slats is small so that when the conveyer is buried in its load 75 it is adapted to slip through the load when the discharge of the load is checked. If desired either the upper or lower run can be used as the conveyer portion, or both the upper and lower runs can act as conveyers. 80

In a conveyer made in accordance with this invention the pitch and width of the links of a chainlike member and the size of the cross bars are of such dimensions that the flour or other substances handled, drops 85 on to the chain and forms a stratum to the depth of the links so that the links with the flour in them form or act as a solid band, supported by the bottom of the trough. On 90 this improvised band is carried the remainder of the load which can be of considerable depth. When a discharge orifice is reached the bottom stratum, which with the links formed the band conveyer, drops through 95 the orifice and thus releases the load above which is thereby discharged through the links and the orifice. If the orifice is blocked the load is carried forward until it meets with some obstruction which stops it such as the driving drum, but the bottom stratum in the links of the chain continues 100 its journey around the drum and becoming the upper run returns on the top of the original load and brings back the surplus until it has filled the whole of the conveyer thereby 105 preventing the entrance of more flour. The chain therefore continues its journey with its links filled with flour until the discharge is

freed. The bars of the chains are as small in diameter as possible in order that the minimum power is required for the chain to pull itself together with its stratum of flour or other substance through the choked load and also for the purpose of causing the minimum damage to the flour or other substance whilst working without a free outlet.

If desired the upper run of chain can run 10 on guides or on a platform.

Referring to the drawings filed here-with:—

Fig. 1 is a diagrammatic elevation of one form of conveyer made in accordance with 15 this invention;

Fig. 2 is a cross section of Fig. 1;

Fig. 3 is a diagrammatic elevation shewing the application of the invention for collecting from each end and discharging at 20 any intermediate point, with or without an overflow discharge;

Fig. 4 is a diagram shewing an application of the invention for collecting the material from one or more inlets conveying the 25 material by the top run, and delivering through the bottom run the bottom run conveying surplus material if desired to one or more overflow outlets;

Fig. 5 is a diagram shewing the application 30 of this invention for collecting from two intermediate inlets and discharging at opposite ends.

Similar reference letters are shewn for 35 similar parts in all the figures.

Fig. 6 is a chain like structure composed of a series of wide sprocket links adapted to run on two drums *b* *c* each disposed between a pair of sprocket wheels *b*¹ and *c*¹. The sprocket wheel *c*¹ forms the driver and the 40 chain is travelling in the direction shewn by the arrows.

Surrounding the chain is a casing or tube *d* provided with an opening *e* for the material to enter and an opening *f* for the material to be drained off. *g* are scrapers, *h* are guides and *i* a platform.

In operation the substance enters at *e* and falls through the top run of the chain on to the lower run where it is conveyed to the 50 discharge opening *f*.

An overflow *k* may be provided at any point between the inlet *e* and drum *b* and an overflow *k*¹ anywhere between the discharge *f* and drum *c*.

When the outlet *f* is blocked the material 55 is discharged through the overflow *k*. If this is also blocked the surplus material is conveyed by the upper run to parts of the chain not fully loaded and back to overflow *k*¹ until that is blocked, when the material 60 chokes the inlet *e* and prevents further material from entering.

If desired a platform *i* instead of the

guides *h* may be substituted a part of the distance.

In Fig. 3 a portion of the material enters the conveyer by inlet *e* and drops through to the under run which conveys the material to outlet *f*, meanwhile another inlet *e*¹ at the other end of the conveyer delivers material 70 on to the platform *i* so that the upper run conveys it as far as the platform extends, which is between inlet *e* and outlet *f*, the material thus dropping through the upper run on to the lower run and through the outlet *f*. 75

In Fig. 4 three inlets *e* *e* *e* are shewn. The material is conveyed by the upper run and discharged at *f* through the lower run, one or more overflow discharges *k* may be provided, scrapers *g* *g* being provided at each 80 end.

In Fig. 5 two intermediate inlets *e* *e*¹ are provided, the inlet *e* delivers on to the upper run and discharges at *f* the inlet *e*¹ delivers through the upper run on to the lower run 85 and discharges at *f*¹.

If desired a series of sprocket chains disposed side by side may be connected together by bars or the like at intervals.

The slats or rods may be very small in 90 diameter say about $\frac{3}{8}$ inch and fairly close together, say about 4" apart.

With a conveyer made in accordance with this invention the flour or other substances may be piled up on the conveyer a foot or 95 more high and moved at a low speed, say for instance a foot or so a minute but any suitable speed may be employed.

It will thus be seen that a conveyer made in accordance with this invention is of great 100 capacity, gentle in action and requires the minimum of power whilst it is practically unchokable. It is suitable for flour, grain, wheaten products in all stages of manufacture also for numerous other substances such as cement, gravel, sawdust etc. 105

What I claim and desire to secure by Letters Patent is:—

A conveyer chain for the purpose described, consisting of a plurality of pivotally connected links, each of said links having a pair of side members and a transverse member, said transverse member lying wholly within the space between said links and thereby constituting a conveyer flight, the 115 links throughout the chain being of uniform height and the transverse member similarly being of uniform height, said transverse members having their heights so proportioned with respect to the distance from center to center of the transverse members that loose material will be conveyed by said chain as by a ribbon through the material. 120

In testimony whereof I have signed my name to this specification.

ARNOLD REDLER.
